MADELEINE PICKERING POWER, OF SPOKANE, WASHINGTON.

PICTURE.

Application filed September 9, 1925. Serial No. 55,326.

My invention relates to pictures. More particularly, my invention relates to the providing of a picture having a background of fabric and that portion of the picture constituting the figure proper formed of cut-out tinfoil, and being what is known as a "cut-out".

Tinfoil is a medium particularly well adapted to reflect light, especially electric light, owing to its ability to be wrinkled, and thereby secures an effect not otherwise readily obtainable. Moreover, wrinkled or embossed tinfoils lend themselves to picture work by reason of the fact that a line may be made thereon by merely pressing with a pencil. However, in other respects, tinfoil does not lend itself to being used for the art of "cut-out" picture-making, since it cannot well be pasted upon the background. The lines to be represented by "cut-out" tinfoil to form the figure may be very fine, such as in the case of a spider-web, and the difficulty in this case in pasting a figure "cut-out" from tinfoil is manifestly due to the lack of proper width or surface upon which to spread the glue or sizing. Where the figure is of larger proportions, objection obtains to using sizing as the means of securing the tinfoil in predetermined position owing to the fact that the sizing is difficult to adhere to the fabric or velvet background. On the other hand, if glue or paste is used as the means of securing tinfoil in predetermined position, serious objection obtains owing to the fact that the tinfoil wrinkles, (which wrinkling obviously is of a character not to be controlled and may be undesired), and the picture is thereby marred.

Moreover, it is practically impossible to use paste or glue without the same showing, and thereby marring the artistic value of the picture. Tinfoil, furthermore, is not adapted to be pasted, for the reason that it so readily tears. In merely cutting out the tinfoil, it brakes or tears. There are sizings that will not contract the tinfoil and wrinkle the same, and such sizings are useful to cause the overlapping tinfoil parts of the picture to adhere as respects each other.

However, such sizings will not secure tinfoil to paper as a background and do not readily cause the tinfoil to adhere to the fabric or velvet. The problem therefore remains of providing, and means for supporting in predetermined position a "cut-out" figure of tinfoil, and such is a primary object of my invention.

Moreover, tinfoil, owing to its great characteristic of reflecting light, lends itself to vivid and brilliant coloring effects, and therefore striking contrasts are very desirable. This gives rise to the importance of a suitable background that has depth to it and does not reflect the light. A primary object of my invention is to provide a suitable background that may emphasize the brilliancy of the figures of tinfoil disposed thereon,—said background not only contributing thus to the artistic value of the picture but also acting as a means for holding the tinfoil in predetermined position.

The above mentioned general objects of my invention, together with others inherent in the same, are attained by the picture illustrated in the following drawings, the same being merely preferred exemplary forms of embodiment of my invention, throughout which drawings like reference numerals indicate like parts:

Figure 1 is a front view of a picture embodying my invention;

Fig. 2 is a fragmentary view in cross-section, illustrating the method of maintaining the tinfoil in position by the nap of the fabric;

Fig. 3 is a view of the parts, with the exception of the tinfoil figure, constituting my invention;

Figs. 4, 5, 6, 7, 8, and 9 are parts cut from tinfoil which assembled constitute the figure illustrated in Fig. 1; and

Fig. 10 is a fragmentary cross-sectional view of a modified form of a picture embodying my invention.

Out of silver-colored tinfoil, a web 10, as represented in Fig. 4, is cut. Likewise, out of silver-colored tinfoil a mushroom figure 11, illustrated in Fig. 5, is cut. Out

of red tinfoil, a member 15, of the form illustrated in Fig. 7, is cut and secured by sizing on the underside of the mushroom figure 11. Out of a green tinfoil, the fairy-like figure 12, as represented in Fig. 9, is cut. Likewise, out of green tinfoil, the ground 13, as represented in Fig. 8, is cut. The fireflies 14, as represented in Fig. 6, are cut out of red colored tinfoil. The green ground 13 may have secured thereto by sizing on its underside a mushroom member 11. The various tinfoil members are then assembled in position as illustrated in Fig. 1, upon the glass 16, disposed in frame 17. The fabric 18 is then placed upon the tinfoil with the nap 19 disposed against the tinfoil and the glass. In Fig. 2, the tinfoil figure is represented by numeral 20. Against the fabric, the corrugated cardboard 21 is operatively secured to hold the other members in operative position against the frame 17.

Where the picture involves a water scene, or for any other reason, some particular effect is desired, where tinfoil may not be desired, in the modified form illustrated in Fig. 10 I secure on top of the fabric or velvet nap 19 a cloth, known as artists' gauze, 22, which is of a color well adapted to give the effect of water or sky. Between this gauze and the glass, the figure formed of tinfoil 20 is disposed as shown.

The operation of the parts constituting my invention is as follows: The tinfoil, being so very fragile or subject to tearing so very readily presents the difficult problem of being held in position, when used as the material for "cut-outs". This difficulty I overcome by disposing a fabric, having a deep nap, such as velvet, as the means to press the tinfoil figure against the glass. This fabric is also preferably used, unless the effect desired prevents, as the background for the picture. It is peculiarly adapted for use in connection with tinfoil where depth is desired to absorb the light and make a rich black background as a contrast to the bright colored tinfoil constituting the "cut-out" figure portion of the picture. Thus, the velvet performs two functions; first, as a means for holding the tinfoil in position; and, second, as a background for the picture itself. The velvet is operatively held against the tinfoil and glass with the nap under a slight pressure, so that the tinfoil is securely and delicately held in position, so that if the "cut-out" figure be of the fine lines of the spider-web, nevertheless the same is held securely in position and without distortion of its lines as originally designed. Every little filament of the nap operates as a minute finger to assist in holding the fragile tinfoil in position. Manifestly, there is no problem of gluing the filament of the tinfoil to the background, and consequently no discoloring of the back-

ground with paste, or shrinking of the tinfoil, resulting in a mar by reason of paste or glue.

Where there is a large piece of tinfoil, such as the ground member 8, a touch of sizing, which may not well adhere to the tinfoil, may be employed as a means of roughening the under-surface of the tinfoil and thus assist in securing the said member to the background. In short, it is not so much the adhesive property of the paste or the sizing in joining the tinfoil to the fabric as it is the fact that the surface is roughened, so that the nap is enabled to hold the section possibly a little more firmly. However, it is to be distinctly understood that the nap ordinarily is sufficient to hold even the larger sections in place without the application of any paste or glue as between the tinfoil and the nap.

In the modified form, the operation of the nap to act as a holding means for the tinfoil is accomplished through the intermediately disposed gauze 22. The velvet may be combined with varied colored gauze to get color effects as may be desired for the particular picture in question.

My invention is particularly adapted and effective in producing the proper light effects desirable in depicting fairy subjects.

Obviously, changes may be made in the form, dimensions, and arrangement of the parts of my invention, without departing from the principle thereof, the above setting forth only preferred forms of embodiment.

I claim:—

1. A picture comprising a member having a napped surface, a transparent member, and a metallic foil figure disposed between and engaging said napped surface and said transparent member.

2. A picture comprising a fabric having a light-absorbing napped surface, a transparent member, and a metallic foil figure disposed between and engaging said fabric and said transparent member.

3. A picture embodying a fabric member having a relatively long compact nap, a figure cut from light-reflecting metallic foil disposed on said fabric; a glass fixedly disposed against said foil figure and fabric whereby said figure is pressed against and held in place by the fabric nap pressing the foil against said glass, whereby said foil figure is held in predetermined position and whereby is provided by said nap, means for the absorption of light which affords a striking contrast of brilliancy between said foil and said background.

4. A picture embodying a fabric member having a relatively long compact light-absorbing, dark nap, a figure cut from colored light-reflecting metallic foil disposed on said fabric; a glass fixedly disposed against said

foil figure and fabric whereby said figure is pressed against and held in place by the nap pressing the foil against said glass, whereby said foil figure is held in predetermined position and whereby is provided by said nap means for the absorption of light to thereby afford a striking contrast of brill-

liancy between said foil and said background.

In witness whereof, I hereunto subscribe **10** my name this 12th day of August, A. D. 1925.

MADELEINE PICKERING POWER.
